CLAIM

I claim the ornamental design for a regenerative media filter, as shown and described.

DESCRIPTION

FIG. 1 is a left elevation view of the filter;

FIG. 2 is a front elevation view of the filter;

FIG. 3 is a right elevation view of the filter;

FIG. 4 is a back elevation view of the filter;

FIG. 5 is a rear perspective view of the filter;

FIG. 6 is a front perspective view of the filter;

FIG. 7 is a top plan view of the filter; and,

FIG. 8 is a bottom plan view of the filter.

The broken line showing of a regenerative media filter is included for the purpose of illustrating portions of the article and forms no part of the claimed design.
